UNITED STATES PATENT OFFICE.

JOHN O. MILLER, OF CHICAGO, ILLINOIS, ASSIGNOR TO THE BRUNSWICK-BALKE-COLLENDER COMPANY, OF CHICAGO, ILLINOIS, A CORPORATION OF DELAWARE.

DESIGN FOR A GRILLE FOR PHONOGRAPH CABINETS.

Application filed August 14, 1922. Serial No. 3,382. Term of patent 14 years.

To all whom it may concern:

Be it known that I, JOHN O. MILLER, a citizen of the United States, residing at Chicago, in the county of Cook and State of Illinois, have invented a new, original, and ornamental Design for Grilles for Phonograph Cabinets, of which the following is a specification, reference being had to the accompanying drawing, forming a part thereof, in which the figure is a plan view showing the invention.

I claim:

The ornamental design for a grille for phonograph cabinets as shown.

JOHN O. MILLER.
